(57) **CLAIM**

We claim the ornamental design for a tool case, as shown and described.

DESCRIPTION

FIG. 1 is a front perspective view of a first embodiment of the tool case;

FIG. 2 is a rear perspective view of the first embodiment;

FIG. 3 is a top view of the first embodiment;

FIG. 4 is a left side view of the first embodiment;

FIG. 5 is a front view of the first embodiment;

FIG. 6 is a rear view of the first embodiment;

FIG. 7 is a left side view of the first embodiment;

FIG. 8 is a bottom view of the first embodiment;

FIG. 9 is a front perspective view of the first embodiment, with the case open;

FIG. 10 is a perspective view of the underside of the first embodiment, with the case open;

FIG. 11 is a perspective view of the front of a second embodiment of the tool case;

FIG. 12 is a bottom perspective view of the rear of the second embodiment;

FIG. 13 is a top view of the second embodiment;

FIG. 14 is a right hand side view of the second embodiment;

FIG. 15 is a front view of the second embodiment;

FIG. 16 is a rear view of the second embodiment;

FIG. 17 is a left hand side view of the second embodiment;

FIG. 18 is a bottom view of the second embodiment;

FIG. 19 is a perspective view of the front of the second embodiment, with the case open; and,

FIG. 20 is a right hand side view of the second embodiment, with the case open.

The design consists of the visual features of the entirely of the tool case as shown in the drawings.
